UNITED STATES PATENT OFFICE.

BERNARD JACQUART, OF SOUTH RIVER, NEW JERSEY.

BRICK OR TILE COVERING FOR BEAMS.

SPECIFICATION forming part of Letters Patent No. 674,089, dated May 14, 1901.

Application filed February 26, 1901. Serial No. 48,937. (No model.)

To all whom it may concern:

Be it known that I, BERNARD JACQUART, a citizen of the United States, and a resident of South River, in the county of Middlesex and State of New Jersey, have invented a new and useful Improvement in Brick or Tile Coverings for Beams, of which the following is a specification.

My invention relates to an improvement in brick or tile coverings for beams, with the object in view of providing a structure which will entirely cover the exposed portions of the beam, preferably provided with an enameled face.

15 A further object is to provide a structure composed of an intermediate series of bricks or tiles located along one surface of the beam, which bricks or tiles are securely locked in position by two series of bricks or tiles which 20 form the adjacent bases of the arches which span the spaces between the said beam and the next succeeding beams on either side.

A further object is to provide an enameled brick or tile covering for beams in which the 25 base or locking bricks or tiles of the arches are not exposed, a single joint being formed at the meeting corners of the intermediate brick or tile, the locking bricks or tiles, and the adjacent arch bricks or tiles, the enameled face of the intermediate brick or tile forming a continuation of the enameled faces 30 of the said adjacent arch bricks or tiles.

A practical embodiment of my invention is represented in the accompanying drawings, 35 in which—

Figure 1 represents in vertical cross-section a portion of a ceiling with my improved beam-covering applied to a metallic I-beam. Fig. 2 is an inverted plan view of the same. Fig. 40 3 is a section taken in the plane of the line A A of Fig. 1. Fig. 4 is a view in perspective of one of the locking bricks or tiles, and Fig. 5 is a view in perspective of one of the intermediate bricks or tiles.

45 The metallic I-beam represented in the accompanying drawings is denoted by *a* and the bricks or tiles which form the arches by *b*. The bricks or tiles which are in engagement with the I-beam and which form the bases of the 50 arches are denoted by *c*. The intermediate bricks or tiles, which are locked in position along one face of the beam *a* by the bricks or

tiles *c*, are denoted by *d*. The reveals or exposed surfaces of the arch bricks or tiles *b* and the exposed surface of the intermediate bricks 55 or tiles *d* are provided with an enameled facing or surface *e*.

As all of the locking bricks or tiles *c*, which form the bases of the arches which span the spaces between the different beams, are quite 60 similar in form, I will proceed to describe one only of the said bricks or tiles.

The brick or tile *c* is provided with a slanting outer side *f*, against which the next adjacent brick or tile of the arch abuts. The inner side *g* of the brick or tile is arranged to 65 abut against the web of the I-beam.

The front of the brick or tile is provided with a locking-tongue *h*, running lengthwise thereof, formed by providing a V-shaped 70 groove *i* in the outer front corner of the brick or tile and cutting away the inner front corner of the brick or tile, as shown at *j*, preferably forming an inclined surface arranged to correspond with the inner surface of one flange 75 of the base of the I-beam *a*.

The intermediate brick or tile has an interlocking connection with the two locking bricks or tiles, in the present instance by providing the inner face of the intermediate 80 brick or tile with a wide dovetailed groove *k*, extended lengthwise therethrough, the groove being of sufficient width to receive therein the base of the beam and the outwardly-extended tongues *h* of the two adjacent locking bricks 85 or tiles *c*.

The inner face of the brick or tile *d* upon opposite sides of the groove is so arranged that it will snugly fit the angles formed in the outer front corners of the two locking bricks 90 or tiles *c*, a single joint being formed upon each side of the beam between the meeting corners of adjacent arch bricks or tiles, the locking brick or tile, and the intermediate brick or tile, thus entirely concealing the locking brick or tile *c*. The bottom of the dovetailed groove *k* in the intermediate brick or tile is preferably made to snugly fit the outer ends of the tongues *h* of the two locking bricks or tiles *c* and the outer face of the base 95 of the I-beam *a*.

By providing the beam with the covering hereinbefore set forth it will be seen that I am enabled to entirely do away with the ne-

cessity of providing the locking bricks or tiles *c* with an enameled face, thus materially reducing the expense of producing the covering.

The bricks or tiles *c* may be dried and burned within the kiln without requiring the special care and space that is necessary when the enameled facing is applied thereto. Furthermore, a fewer number of exposed joints is obtained, the only exposed joint in the covering being the one at the angle formed between the intermediate brick or tile and the arch brick or tile *b* at each side of the beam.

It is evident that slight changes might be resorted to in the form, construction, and arrangement of the several parts without departing from the spirit and scope of my invention. Hence I do not wish to limit myself strictly to the structure herein set forth; but

What I claim is—

1. A beam-covering comprising an intermediate brick or tile and a pair of locking bricks or tiles having an interlocking connection with the back of the intermediate brick or tile for holding it in position, substantially as set forth.

2. A beam-covering comprising an intermediate brick or tile, arch bricks or tiles and locking bricks or tiles having an interlocking engagement with the intermediate brick or tile and being concealed by the intermediate brick or tile and the adjacent arch bricks or tiles, substantially as set forth.

3. A beam-covering comprising an intermediate brick or tile located along the outer face of the beam and a pair of locking bricks or tiles upon opposite sides of the beam having tongue-and-groove connections with the intermediate brick or tile for locking the intermediate brick or tile, in position, substantially as set forth.

4. A beam-covering comprising an inter-

mediate brick or tile located along one face of the beam and having a dovetailed groove therein and a pair of locking bricks or tiles upon opposite sides of the beam having 45 tongues thereon engaging said groove for locking the intermediate brick or tile in position, substantially as set forth.

5. In combination, an intermediate brick or tile having a dovetailed groove therein, a 50 beam having a flanged base located in the said groove and a pair of locking bricks or tiles upon opposite sides of the beam having portions thereof interposed between the base of the beam and the sides of the groove in 55 the intermediate brick or tile for locking the intermediate brick or tile in position, substantially as set forth.

6. An enameled covering for beams comprising an enameled intermediate brick or 60 tile, enameled arch bricks or tiles and intermediate non-enameled locking bricks or tiles upon opposite sides of the beam, the said non-enameled locking bricks or tiles being concealed by the intermediate enameled brick or 65 tile and the adjacent enameled arch bricks or tiles, substantially as set forth.

7. A locking brick or tile having an outwardly - extended tongue formed along its outer face by providing a V-shaped groove in 70 its outer front edge and cutting away a portion of its inner front edge, substantially as set forth.

In testimony that I claim the foregoing as my invention I have signed my name, in presence of two witnesses, this 8th day of February, 1901.

BERNARD JACQUART.
